UNITED STATES PATENT OFFICE.

GEORGE B. KYLE, OF ST. LOUIS, MISSOURI, ASSIGNOR TO THE MEASUREGRAPH COMPANY, OF ST. LOUIS, MISSOURI, A CORPORATION OF DELAWARE.

FABRIC MEASURING AND COST COMPUTING MACHINE.

Application filed November 7, 1921. Serial No. 513,303.

To all whom it may concern:

Be it known that I, GEORGE B. KYLE, a citizen of the United States, residing in the city of St. Louis, and State of Missouri, have invented new and useful Improvements in Fabric Measuring and Cost Computing Machines, of which the following is a specification.

This invention relates to fabric measuring and cost computing machines and particularly to the type of machine which comprises a marking device or knife for marking the fabric at the point where it is to be cut off after a measurement has been made. 10 The type of machine referred to, also includes a movable presser roller which is raised automatically from contact with the measuring roller when the marking knife is actuated. In the regular operation of such a machine, the indicating mechanism is reset to zero by pressing a resetting button after the presser roller has been raised by the operation of the knife. But in making measurements with such a machine it sometimes 15 happens that a customer may request a given number of yards, for example, five yards, and when the measuring movement is nearly completed, may desire to purchase a length off another pattern or bolt. When this occurs it is, of course, impracticable to operate the knife because this would snip the edge of the fabric. However, it is necessary to effect the raising of the presser roller in order to enable the fabric to be removed. 20 The general object of the present invention is to provide a machine of this kind with means independent of the knife which can be used when desired to effect the raising of the presser roller without the usual 25 previous actuation of the knife; and also to provide such construction with means operating simultaneously to effect the resetting of the indicating mechanism to zero.

It might be supposed that the difficulty 30 pointed out above could be overcome by pulling the fabric laterally from between the rollers but when this is done there is a tendency for the rollers to produce a mark on the fabric which might detract from its value.

Further objects of the invention will appear hereinafter.

The invention consists in the novel features, and in the general combination of 55 parts to be particularly described herein-

after, all of which contribute to produce a simple and efficient special resetting attachment for fabric measuring and cost computing machines. A preferred embodiment of my invention will be described in the following specification, while the broad scope of my invention will be pointed out in the appended claims.

In the drawing:

Figure 1 is a plan of a machine embodying my invention;

Figure 2 is an end elevation of the machine shown in Figure 1 with the casing partially broken away, and showing the relation of the parts in dotted lines;

Figure 3 is a vertical section through the base plate of the machine, the casing being removed; this view particularly illustrates the means for driving the indicating mechanism;

Figure 4 is a horizontal section taken about on the level of the line 4-4 of Figure 2 and illustrating details of the presser roller;

Figure 5 is a side elevation of the machine with the casing broken away, and shown partially in section;

Figure 6 is an end view of the machine with the casing broken away; and

Figure 7 is a vertical section taken 85 through the axis of the clutch shaft.

The machine in which I have embodied this invention comprises a casing 1, the upper side of which is provided with a dial 2 with which movable pointers 3 and 4 co-operate to indicate the length measured. These pointers constitute part of the indicating mechanism which also includes two computing charts 5 and 6 which are visible through two windows 7 and 8 formed in the upper side of the casing. In the operation of the machine the goods to be measured is pulled through a gap or measuring throat 9 so that it passes between a measuring roller 10 and a presser roller 11. (See Fig. 2.) 100 The rotation of the measuring roller is imparted to the charts 5 and 6 through suitable driving mechanism. I provide resetting means to reset the indicating mechanism to zero; this means is actuated automatically 105 by the operation of the marking means. I also provide a hand-operated member independent of the marking-means the movement of which raises the presser roller and also actuates the resetting means to reset the 110

indicating mechanism to zero. I shall now describe the driving mechanism and means which I may employ to effect the desired mode of operation. The shaft of the measuring roller carries a pinion 12 (see Fig. 3) which drives a gear wheel 13 mounted on a hub 14 which operates as a clutch member co-operating with a sliding clutch member 15 which carries a rigid pinion 16. (See Fig. 7.) The pinion 16 in turn drives a large gear 17 mounted to rotate on an arbor 18. This gear 17 carries a rigid pinion 19 which meshes with an idler 20 and this idler meshes with two gear wheels 21 and 22 which are rigidly mounted on the shafts of two take-up rollers 23 and 24. (See Fig. 2.) In this way, when the clutch 7 is closed, the rotation of the measuring roller will effect a rotation of the take-up rollers 23 and 24 in a direction indicated by the arrows in Fig. 2. This will draw the charts off of a supply drum 25 which is provided with resetting means in the form of a spring 25^a which operates to maintain the charts in tension and to return the charts to the zero position after a measuring movement. These features of the machine have been fully described in Patent No. 1,390,323, issued to John L. Wheeler, on the 13th day of September, 1921. The charts 5 and 6 carry computed numbers which correspond to different price rates shown on two scales 27 and 28 which co-operate with the charts, and in addition to this, one of the charts bears numbers such as the number "3" which indicates the number of yards which the measuring pointers 3 and 4 indicate.

The presser roller 11 is mounted upon a movable frame comprising a rock shaft 29 (see Figures 2 and 4), the ends of which are rotatably supported in the frame of the machine. For this purpose the inner end of the rock shaft 29 is secured in a vertical frame plate 30 which supports the driving gear train which has already been described. This rock shaft 29 carries an arm 31 which carries an arbor rotatably supporting the presser roller. Springs 32 are provided which connect with short arms on the presser roller frame (see Figure 4) and these springs tend to hold the presser roller against the upper face of the measuring roller.

The machine is provided with a marking device or knife 33 which is mounted on a horizontal pivot bolt 34 (see Figure 6). This knife carries a blade 35 which co-operates with a fixed blade 36 when the knife is depressed, to cut the edge of the fabric and mark the quantity measured, to enable the same to be cut off at the proper point. As the knife lever descends, its edge actuates an arm 37 which projects from the rock shaft 29 of the presser roller frame and this effects the raising of the presser roller. That

is to say, it moves the presser roller up to separate it from the measuring roller. When this occurs, a spring-pressed latch 38, Fig. 4, snaps over the arm 37 and holds the presser roller up against the action of the springs 32.

When this machine is being used in the regular way to measure off lengths to be cut from a bolt or roll, then the knife lever is operated in the manner just described. However, in order to adapt the machine for measuring remnants and to enable it to be set back to zero after the measure has been taken, without actuating the knife lever, I provide a hand-operated member independent of the knife lever which will effect the raising of the presser roller and which will also effect the opening of the clutch 14-15, thereby enabling the spring roller 25 to return the indicating mechanism to zero. For this purpose the clutch member 15 is rigidly secured upon a clutch shaft 39 (see Fig. 7) which is mounted to slide in a bracket 40 at its outer end, and in the aforesaid vertical frame plate 30, at its inner end. A clutch spring 41 tends to hold this clutch closed. In this connection it should be understood that the hub or clutch member 14 is mounted to rotate in a part of the bracket 40 and permits the clutch shaft 39 to slide freely through it. With this construction it is evident that by shoving in on the outer end of the clutch shaft 39, the clutch will be opened.

The inward movement of the clutch shaft 39 in this way may be accomplished by means of a hand-operated member in the form of a bell crank lever 42, Fig. 5, which projects through a slot 43 in the wall of the casing at one end. The vertical arm 44 of this lever is connected by a link 45 with a short lever 46 which engages the outer end of the clutch shaft near the pivot pin 47 which supports the lever 46 on the underside of the horizontal bracket plate 48 with- in the machine.

In order to effect the raising of the presser roller, the arm 44 is attached to a link 49 the inner end of which actuates a bell crank lever 50 supported on a suitable bracket 51, and the horizontal arm of this lever is attached to a twisted link 52 which extends upwardly and is attached to an arm 53 carried by a reduced extension 54 of the rock shaft 29. (See Figs. 4 and 6.) The outer end of the bell crank lever 42 is provided with a thumb plate 42^a and it will be evident that when this thumb plate is depressed, the bell crank lever will operate to open the clutch, and through the medium of the link 52 and bell crank lever 50, will also operate to raise the presser roller. In the present embodiment of the invention, opening the clutch will actuate the resetting means and effect the return of the indicat-

ing mechanism to zero; and in addition to this, the latch 38, Fig. 4, will co-operate with the arm 37 to hold the presser roller up to enable the next remnant to be introduced into the measuring throat 9 and properly positioned therein before the latch 38 is moved by the operator of the machine, to release the presser roller and permit it to descend upon the measuring roller.

10 It has not seemed necessary to describe the means for effecting the driving of the pointers 3 and 4 because this means has been fully described in the patent referred to above. In this connection it should be 15 noted that the charts afford means for indicating the length measured in addition to the cost computed at various price rates per yard.

It is understood that the embodiment of 20 the invention described herein is only one of the many embodiments my invention may take, and I do not wish to be limited in the practice of my invention nor in my claims, to the particular embodiment set 25 forth.

What I claim is:

1. In a fabric measuring machine comprising a presser roller, and marking means to mark the edge of the fabric, and to raise 30 the presser roller when the said means is actuated, the combination of a measuring roller, indicating mechanism, resetting means, for returning the indicating mechanism to the zero position, a movable member independent of the marking means, and means actuated by said member for raising the presser roller and for simultaneously actuating the resetting mechanism to reset the indicating mechanism to zero.

40 2. In a fabric measuring machine comprising a presser roller, and marking means to mark the edge of the fabric, and to raise the presser roller when the said means is actuated, the combination of a measuring 45 roller, indicating mechanism actuated by said measuring roller, resetting means in the form of a spring for returning the indicating mechanism to the zero position, a movable member independent of the marking 50 means, and means actuated by said member for raising the presser roller and for simultaneously actuating the spring to reset the indicating mechanism to zero.

55 3. In a fabric measuring machine comprising a presser roller, and marking means to mark the edge of the fabric and to raise the presser roller when the said means is actuated, the combination of a measuring roller, indicating mechanism, a clutch and 60 driving mechanism driven by the measuring roller for driving the indicating mechanism, means for resetting the indicating mechanism to zero after the clutch has been opened, a movable member independent of 65 the marking means, and means actuated by

said member for raising the presser roller and for simultaneously opening the clutch to permit the resetting mechanism to effect the resetting of the indicating mechanism to zero.

4. In a fabric measuring machine comprising marking means for marking the edge of the fabric, and a presser roller with a movable frame operable so as to be raised by the actuation of the marking means, the combination of a measuring roller, indicating mechanism, a clutch and driving mechanism driven by the measuring roller for driving the indicating mechanism, means for resetting the indicating mechanism to zero after the clutch has been opened, a hand-actuated member independent of the marking means, means actuated by said member for opening the clutch, and means also actuated by the same and connected with the presser roller frame for raising the same.

5. In a fabric measuring machine comprising marking means for marking the edge of the fabric, and a presser roller with a movable frame operable so as to be raised by the actuation of the marking means, the combination of a measuring roller, indicating mechanism, a clutch and driving mechanism driven by the measuring roller for driving the indicating mechanism, means for resetting the indicating mechanism to zero after the clutch has been opened, a hand-actuated member independent of the marking means, means actuated by said member for opening the clutch, and means also actuated by the said member and connected with the presser roller frame for raising the same, and means for latching the presser roller frame in its raised position.

6. In a fabric measuring machine comprising marking means for marking the edge of the fabric and a presser roller mounted in a rocker frame operating to be raised by the actuation of the marking means, the combination of a measuring roller, indicating mechanism, a clutch, driving mechanism driven by the measuring roller for driving the indicating mechanism, means for resetting the indicating mechanism to zero after the clutch has been opened, a hand-actuated member independent of the marking means, means actuated by said member for opening the clutch, and means connecting the hand-actuated member with the presser roller frame for rocking the same to raise the presser roller away from the measuring roller.

7. In a fabric measuring machine comprising marking means for marking the edge of the fabric and a presser roller mounted in a rocker frame operating to be raised by the actuation of the marking means, the combination of a measuring roller, indicating mechanism, a clutch, driv-

ing mechanism driven by the measuring roller for driving the indicating mechanism, means for resetting the indicating mechanism to zero after the clutch has been opened, a hand-actuated member independent of the marking means, means actuated by said member for opening the clutch, and means connecting the hand-actuated member with the presser roller frame for rocking the same to raise the presser roller away from the measuring roller, and a hand-actuated latch for latching the presser roller frame in its raised position.

8. In a fabric-measuring machine, the combination of a measuring roller, a presser-roller, a presser-roller frame carrying the same and mounted to move so as to enable the presser-roller to co-operate with the measuring roller during the measuring operation, indicating mechanism, a clutch and driving mechanism driven by the measuring roller for driving the indicating-mechanism, a bell-crank lever, means actuated by the bell-crank lever for opening the clutch, means actuated by the bell-crank lever for moving the presser-roller away from the measuring roller, and means for returning

the indicating mechanism to zero after the clutch has been opened.

9. In a fabric-measuring machine, the combination of a frame including a substantially vertical frame plate, a measuring roller supported by the frame plate, a rocking frame mounted in said frame, a presser-roller carried thereby to cooperate with the measuring roller during the measuring movement, said rocking-frame having a shaft extending beyond said frame plate, indicating-mechanism, a clutch and driving mechanism driven by the measuring roller for driving the indicating mechanism, a casing, a hand-actuated lever within the casing and projecting to the exterior thereof, means actuated by said lever and connected with said shaft to raise the rocking frame and thereby move the presser-roller away from the measuring roller, means also actuated by said lever to open the clutch, and means for returning the indicating-mechanism to zero after the clutch has been opened.

In testimony whereof, I have hereunto set my hand.

GEO. B. KYLE.
